[57] CLAIM

The ornamental design for an article of flatware or similar article, as shown and described.

DESCRIPTION

FIG. 1 is a front elevational view of an article of flatware showing my new design as embodied in a fork; FIG. 2 is a side elevational view thereof from the right of FIG. 1;

FIG. 3 is a rear elevational view of the article of flatware of FIG. 1;

FIG. 4 is an end view from the top of FIG. 1;

FIG. 5 is an enlarged cross-sectional view taken along line 5—5 of FIG. 1;

FIG. 6 is an enlarged cross-sectional view taken along line 6—6 of FIG. 1;

FIG. 7 is an enlarged cross-sectional view taken along line 7—7 of FIG. 1;

FIG. 8 is an enlarged cross-sectional view taken along line 8—8 of FIG. 1;

FIG. 9 is an enlarged cross-sectional view taken along line 9—9 of FIG. 1;

FIG. 10 is a front elevational view of an article of flatware showing my new design as embodied in a spoon;

FIG. 11 is a side elevational view from the left of FIG. 10;

FIG. 12 is a rear elevational view of the article of FIG. 10;

FIG. 13 is an end view from the top of FIG. 10;

FIG. 14 is an enlarged cross-sectional view taken along line 14—14 of FIG. 10;

FIG. 15 is an enlarged cross-sectional view taken along line 15—15 of FIG. 10;

FIG. 16 is an enlarged cross-sectional view taken along line 16—16 of FIG. 10;

FIG. 17 is an enlarged cross-sectional view taken along line 17—17 of FIG. 10; and

FIG. 18 is an enlarged cross-sectional view taken along line 18—18 of FIG. 10.

The sides opposite the handle portion shown in FIGS. 2 and 11 are mirror images of the respective sides shown. The distinguishing feature of my new design for an article of flatware resides in the handle configuration.
